UNITED STATES PATENT OFFICE

ARTHUR W. TUCKER, OF SAN ANTONIO, TEXAS

COIN-CONTROLLED CIRCUIT CLOSER

Application filed September 5, 1928. Serial No. 304,050.

My invention relates to coin controlled circuit closers and has as one of its objects the provision of an automatic circuit closer for controlling an electrical device such as 5 an electric fan arranged within a public toilet or other small compartment.

The invention further provides a circuit closed wherein a movable contact is actuated and held in circuit closing position by a movable object such as a swinging door so that 10 upon insertion of a predetermined coin an electrical circuit will be completed as long as the movable contact is held in circuit closing position.

With the preceding and other objects and advantages in mind, the invention consists in the novel combinations of elements, constructions and arrangement of parts and operations to be hereinafter specifically referred 20 to, claimed and illustrated in the accompanying drawings, wherein:—

Figure 1 is a perspective of a compartment having my invention installed therein.

Figure 2 is a diagrammatic view of the 25 electrical circuit embodied in the invention.

Figure 3 is a vertical sectional view of the invention.

Figure 4 is a similar view taken at right angles to Figure 3 and taken on the line 30 4—4 of Figure 3.

Figure 5 is a transverse horizontal section taken on line 5—5 of Figure 3.

Referring to the invention in detail, a substantially rectangular casing 5 of increased 35 width at its lower end to constitute a coin compartment 6 is provided, and is adapted to be supported on a wall of a compartment adjacent the hinged end of a door 7 as disclosed in Figure 1.

To support a pair of cooperating contacts, a horizontally disposed channel shaped member 8 is supported within the casing and extends to the side walls thereof as illustrated in Figure 4. At one end the channel shaped member is formed with a rectangular tubular guide 9 through which a relatively long non-conducting block 10 passes. The non-conducting block 10 is slidable in the channel shaped member and is normally urged to a 40 position where one end projects through an

elongated opening 11 in one of the side walls of the casing by means of a contractile spring 12 having one end secured to an upstanding lug 13 projecting from the upper face of the non-conducting block and its other end anchored to a clip 14 mounted upon the inner face of such side wall. A small non-conducting block 15 is secured within the channel shaped member at the opposite end wall of the casing. Vertically disposed coin receiving slots 16 are formed in the opposed vertical faces of the non-conducting blocks and as disclosed in Figure 5 are located in transverse alinement. The combined cross sectional area of these slots are such as to snugly accommodate a coin of predetermined denomination when the block 10 is moved into abutting relation with the block 15. 55 60 65

To facilitate the passage of coins through the slots their rear walls 17 diverge from the lower ends thereof. Contact strips 18 are secured within the slots and extend the entire length of the divergent walls thereof. At their upper ends, these contact strips are attached to binding posts 19 secured to the upper faces of the blocks 10 and 15. 70 75

To conduct coins into the slots 16, a vertically disposed relatively flat tubular coin guide 20 is supported in vertical alinement with the slots by horizontal brackets 21 extending from the rear wall of the casing. The upper end of this coin guide extends to the top wall of the casing and communicates with a coin entrance slot 22. 80

To conduct electrical energy to the conductor strips to complete an electrical circuit to a fan 23 or other electrical device supported within the compartment, the following circuit is provided: Feed wires 24 from the usual house circuit or other supply source are brought into the upper end of the casing through an opening 25 in one of the side walls thereof. These lead wires are connected to binding posts 26 carried by an insulating block 27 supported within the casing. A connector 28 connects the binding posts 26 and the binding post 19 on the movable block. Conductors 29, one of which is connected with one of the binding posts 26 and the binding post 19 carried by the block 15 pass from 85 90 95 100

the casing through the opening 25 and are electrically connected with the fan 23.

To shift the movable block 10 inwardly to abut the block 15, an angle plate 30 projects from the inner face of the door 7 at its hinged end in the path of the projecting end of the movable block. It will be observed that when the door assumes a closed position, the angle plate will strike the movable block 10 to move it inwardly and retain it in this position as long as the door remains closed. While the blocks 10 and 15 are in abutting relation as stated, a coin dropped into the slots 16 will be held between the blocks. However, upon the return of the movable block to normal position, the coin will fall into the coin compartment by way of an opening 18^a in the bottom of the channel shaped member.

For the purpose of gaining access to the coin compartment, the front wall of the lower part of the casing is provided with a vertically movable sliding door 31 held between vertically extending guides 32 upon the inner faces of the side walls of the casing and the side edges of the front wall of the latter. A finger engaging lip 33 is provided on the upper end of the door whereby the latter is raised and lowered. A conventional lock 34 is associated with the front wall of the casing to prevent the unauthorized opening of the latter.

In order to gain access to the circuit closing mechanism, a second vertically movable slideable door 35 is mounted between parallel guides 36 and adjacent side edges of the casing front wall above the coin compartment. A grasping knob 37 projects from the inner face of the door 35 by means of which this door may be raised and lowered by the insertion of the human hand into the casing through the coin compartment.

In practise, one entering the compartment who desires to make use of the fan, places a coin of predetermined value into the slot 22. As the coin falls into the slots 16 of the blocks 10 and 15 which are at this time in abutting relation it contacts with the contact strips 18 and completes the electrical circuit to the fan. However, while my disclosure sets forth an electric fan, this is merely illustrative as the invention contemplates the use of any other desired electrical device in lieu of the fan.

What is claimed is:

1. In combination, a compartment having a hinged door, a casing supported within the compartment, normally separated fixed and movable contacts in the casing, and means operable by closing of the door to actuate the movable contact to a position where both of such contacts will be engaged by a coin inserted into the casing to complete an electrical circuit.

2. In a circuit closer, a casing, a non-conducting block having a coin slot in its inner

face, a longitudinally movable non-conducting block arranged in horizontal alinement with the first mentioned block and also having a coin slot in its inner face, means normally urging the longitudinally movable block away from the first mentioned block, contact strips held in the coin slots to be engaged by a coin received in the slots to establish an electrical connection when the movable block is held against the first mentioned block. 70

3. In a circuit closer, a casing, a non-conducting block having a coin slot in its inner face, a longitudinally movable non-conducting block arranged in horizontal alinement with the first mentioned block and also having a coin slot in its inner face, means normally urging the longitudinally movable block away from the first mentioned block, contact strips held in the coin slots to be engaged by a coin received in the slots to establish an electrical connection when the movable block is held against the first mentioned block, and a coin guide arranged in the casing above the blocks. 80

4. In a coin controlled circuit closer, a casing having an opening in one side, normally spaced contacts arranged in the casing and one of which being movable towards and away from the other and having one end projecting through the opening, and means engageable with the projecting end of the movable contact for moving the same towards the fixed contact to engage and hold a coin therebetween and thus complete an electrical circuit. 90

5. In a circuit closer, a casing, a pair of cooperating fixed and movable blocks supported in transverse alinement within the casing and having upwardly diverging slots in their opposed faces, contact strips arranged upon the rear walls of the slots, a spring normally urging the movable block away from the fixed block, means for moving the movable block towards the fixed block 105 and holding it in a position where a coin will be held in the slots therein to complete an electrical circuit through the contact strips. 110

6. In a circuit closer, a casing, a pair of cooperating fixed and movable blocks supported in transverse alinement within the casing and having upwardly diverging slots in their opposed faces, contact strips arranged upon the rear walls of the slots, a spring normally urging the movable block away from the fixed block, means for moving the movable block towards the fixed block and holding it in a position where a coin will be held in the slots therein to complete an 120 electrical circuit through the contact strips, and a coin guide in the casing and arranged to direct coins into the slots. 125

7. In a circuit closer, a casing, a pair of cooperating fixed and movable blocks sup- 130

ported in transverse alinement within the casing and having upwardly diverging slots in their opposed faces, contact strips arranged upon the rear walls of the slots, a spring normally urging the movable block away from the fixed block, one end of the movable block normally projecting from one side of the casing, and a swinging stop engageable with the projecting end of the movable block to depress the latter against the action of the spring.

8. In combination a hinged door, a circuit closer supported adjacent the door including normally separated fixed and movable contacts, and means operable by closing of the door to actuate the movable contact to a position where both of such contacts will be engaged by a coin deposited between the same to complete an electrical circuit.
